SOD CUTTING AND LIFTING IMPLEMENT.

(Application filed Oct. 27, 1898.)

UNITED STATES PATENT OFFICE.

TIMOTHY J. GUNNING AND JOHN B. GUNNING, OF BOSTON, MASSACHUSETTS.

DESIGN FOR A SOD CUTTING AND LIFTING IMPLEMENT.

SPECIFICATION forming part of Design No. 29,737, dated November 29, 1898.

Application filed October 27, 1898. Serial No. 694,744. Term of patent 14 years.

To all whom it may concern:

Be it known that we, TIMOTHY J. GUNNING and JOHN B. GUNNING, of Boston, (Jamaica Plain,) in the county of Suffolk and State of 5 Massachusetts, have invented and produced a new and original Design for a Sod Cutting and Lifting Implement, of which the following is a description.

The accompanying drawings are to be accepted as forming an essential part of this specification.

Of the drawings, Figure 1 is a plan view of a sod cutting and lifting implement, showing our new design. Fig. 2 is a side view of 15 the same.

The leading feature of our design consists in the ogee form of the handle between the opposite end portions and the blade and the parallelism of the opposite end portions and 20 blade.

In the drawings, *a* designates the handle proper, which constitutes one end portion of a sod cutting and lifting implement. *b* designates the other end portion, which extends

upon the blade *c* of the implement. The said 25 end portions and the blade attached to one end portion extend in parallel lines.

d is the shank or body part of the handle, which has an ogee form—that is, a form composed of similar but reverse curves. 30

The blade is slightly rounded at the corners, as at *e*, of the front edge and, with the portion of the end of the handle to which it is attached, extends on a line parallel with the opposite end portion *a* of the handle. 35

What we claim as new is—
The design for a sod cutting and lifting implement, as herein described and illustrated.

In testimony whereof we have signed our names to this specification, in the presence of 40 two subscribing witnesses, this 6th day of October, A. D. 1898.

TIMOTHY J. GUNNING.
JOHN B. GUNNING.
